UNITED STATES PATENT OFFICE.

ANTOINE GLOMINSKI, OF LANSINGBURG, NEW YORK, ASSIGNOR TO D., A. E.,
& N. B. POWERS, OF SAME PLACE.

DESIGN FOR FLOOR-CLOTHS.

Specification forming part of Design No. 831, dated September 16, 1856.

To all whom it may concern:

Be it known that I, ANTOINE GLOMINSKI, of Lansingburg, in the county of Rensselaer and State of New York, have invented and produced a new Design, Pattern, or Figure to be Printed, Stamped, or Used upon Floor Oil-Cloths or other Fabrics; and I do hereby declare that the following is a full and exact description of the same, viz:

The principal or leading object in the pattern is a rosette placed upon a ground of lighter color than itself. This ground is of an eight-pointed star-shaped form, and is surrounded by a darker ground of the same form, from which it is separated by coloring so arranged as to represent a triangular band or molding. This darker ground is surrounded by coloring so arranged as to represent a rounded or semicircular band or molding, which meets at the sides of the pattern and is connected across the angles of the pattern

by a similar band or molding in such manner as to divide the remaining undescribed portion of the pattern into four hexagons of four sides and angles unequal with the other two sides and angles, which hexagons are only fully shown when the pattern is repeated. Upon these hexagons are placed others of lighter ground, with the sides parallel with first. An ornament is placed in the center of each hexagon and upon each crossing of the bands or moldings.

What is claimed as my invention, and desired to be secured by Letters Patent of the United States, is—

The arrangement of ornamental figures forming a design for floor oil-cloths or other fabrics, as shown in the aforesaid drawings.

ANTOINE GLOMINSKI.

In presence of—

CHAS. J. LANSING,
WILLIAM POWERS.
